UNITED STATES PATENT OFFICE.

ALEXANDER ANDERSON, OF LONDON, ONTARIO, ASSIGNOR OF ONE-HALF TO
SARAH C. WALKER, OF CHATHAM, CANADA.

COOKING-STOVE.

SPECIFICATION forming part of Letters Patent No. 378,074, dated February 21, 1888.

Application filed January 14, 1886. Serial No. 188,546. (No model.)

To all whom it may concern:

Be it known that I, ALEXANDER ANDERSON, a subject of the Queen of Great Britain, and a resident of London, in the Province of Ontario, Canada, machinist, have invented a certain new and useful Cooking-Stove, of which the following is a specification.

This invention relates to a close fire-place for cooking; and the object of this invention is to greatly economize fuel and economize space, as well as expense in manufacturing a cooking-stove; and it consists of the improved construction and combination of parts of the same, as will be hereinafter more fully described and claimed, reference being had to the accompanying drawings, wherein—

Figure 1 is a perspective view of a stove embodying my invention. Fig. 2 is another perspective view of same, partly in section. Fig. 3 is an enlarged detail perspective view of a grate which rests on the inclined fire-bottom, and in which coal is consumed when this class of fuel is used in this stove.

A designates the body of the stove, constructed of sheet-iron or other suitable material; B, the sloping or inclined fire-bottom, and C the top of the stove, constructed of cast-iron or other suitable material; D, the ash-pan to catch any fire or ashes which may fall out through the openings K' K', and E is a cold-air chamber between the end of the inclined fire-bottom and the back end of the stove. This cold-air chamber E may be lined with fire-brick or not, as required.

K are openings communicating with the cold-air chamber E and outer air, and are for the purpose of permitting cold air to pass into the chamber E. The cold air passes through the pipe F from the chamber E to the flue G when it is convenient to use this stove with a flue G; but when it is not convenient to use this stove with a flue G a cap, H, is placed on the outer end of pipe F, and the cover I is drawn from over the hole or perforation J, formed in the bottom of the stove, and the cover is removed from the ordinary stove and this stove placed thereon, the perforation in the bottom of this stove being opposite the hole in the ordinary stove, when the cold air passes through the cold-air chamber E and

through the ordinary stove and the pipe connected thereto to the outside of the building.

L designates a door through which the wood fuel may be placed on the fire-bottom B, on which fire-bottom B the fire is kindled and the fuel consumed.

If it is desired to burn coal, a perforated casting similar to a bowl or basket may be placed in the front of the stove through the hole N, so that coal, wood, or any fuel may be burned in this stove.

N N are holes over which the cooking utensils—such as tea-kettle, pots, &c.—containing the food to be cooked are placed. The holes N N on this stove may be connected together by a bridge piece, so that this stove may be made to fit the wash-boiler used on an ordinary cooking-stove; or the top C of this stove may be removed and the wash-boiler supported on the upper edges of the body B, and the holes N N may be made any size that the holes in an ordinary stove are made, so that the iron covers, as well as the wash-boiler, tea-kettle, pots, &c., of any stove in present use will fit equally well on this stove. When it is desired to change the size of the holes N N to fit a smaller kettle, it is done by placing a ring on the inner edge of these holes N N, so that a kettle or pot of a smaller size will fit this stove. An oven may be placed over one or both of these holes N N.

This stove may be mounted on feet, or on a hollow platform of sheet-iron or other suitable material; and from practical tests of this stove provided with this cold-air chamber E and inclined or sloping fire-bottom B it has been found that it will effectively cook the same amount of food of any kind as an ordinary stove, but with this great advantage, that it only requires about one-eighth of the fuel to do the same work that is required by an ordinary stove, thereby making a large saving in fuel to any person using this stove; and this stove is about seven or eight inches high, about twelve inches wide, and two feet six inches long, so that it only occupies a very small space, and, being constructed from only a small quantity of sheet-iron and cast-iron, it is built at a very small expense, so that this stove not only greatly economizes fuel, but occupies only a

small space and is built at a very small cost. A cast-iron flange or fire-brick lining (represented by dotted lines *r* in Fig. 2) may extend up from the inclined fire-bottom B at the 5 front and two sides, to protect the sheet-iron body A from the fire.

Having thus described my invention, what I claim as new, and desire to secure by Letters Patent, is—

- 10 1. In a summer-stove, the combination of a body, A, formed with openings K in the sides thereof, removable top C, formed with holes N N, cold-air chamber E, inclined or sloping fire-bottom B, openings K', and pipe F, substantially as shown and described, and for the purpose specified.
- 15 2. In a summer-stove, the combination of the body A, formed with openings K in the sides thereof, removable cover C, formed with

holes N N, cold-air chamber E, inclined or sloping fire-bottom B, openings K', and perforation K, substantially as shown and described, and for the purpose specified.

3. In a summer-stove, the combination of the body A, formed with perforations K in the 25 sides thereof, removable cover C, formed with holes N N, cold-air chamber E, inclined or sloping fire-bottom B, openings K', pipe F, perforation J in the bottom of said stove, and adjustable cover I, substantially as shown and 30 described, and for the purpose specified.

* In testimony whereof I affix my signature in the presence of the two undersigned witnesses.

ALEXANDER ANDERSON.
